INCINERATING FURNACE

John E. Greenawalt, New York, N. Y.

Application October 28, 1933, Serial No. 695,631
Renewed August 9, 1935

8 Claims. (Cl. 110—15)

My invention has relation to improvements in incinerating furnaces and the method practiced therein, and it consists in the novel features of construction more fully set forth in the specification and pointed out in the claims.

The present furnace is similar to that of my co-pending application, Serial No. 544,973, filed June 17, 1931, in that it is particularly adapted for the burning of refuse including garbage which is charged on an air pervious support and caused to travel through the combustion chamber of the furnace, but in addition to the advantages of the furnace of said application the furnace forming the subject-matter of this application embodies improvements to expedite the ignition of the material and thus insure a longer burning period thereof as the material moves through said combustion chamber. These improvements include means for dividing the combustion chamber into zones through which the material passes successively, the primary zone being subject to a down draft of the gases from the secondary zone under the influence of air or other supporter of combustion moving upwardly through the support and material thereon. The advantage of the opposing drafts in the combustion chamber is the retarding of the movement of the flaming particles and hot gases that serve to ignite the material in order that they may be momentarily concentrated in the region of ignition so as to effect such ignition. In order to effect this result an igniting furnace, or equivalent device, is so disposed that the ignition gases coming therefrom will be effective on the material between the zones in the combustion chamber above mentioned. The advantage of this arrangement, as well as other advantages incident thereto, will be better apparent from a detailed description of the invention in connection with the accompanying drawings, in which:

Figure 1 is a top plan of my improved incinerating furnace with parts broken away; Fig. 2 is a vertical longitudinal section taken through a medial plane and indicated by the line 2—2 of Fig. 1; Fig. 3 is a vertical cross-section through the furnace taken on a plane indicated by the zig-zag line 3—3 of Fig. 2; and Fig. 4 is a vertical cross-section taken through the furnace on a plane indicated by the line 4—4 of Fig. 2.

Referring to the drawings, 1, 1 represents the side walls of the furnace surmounted by the arched roof 2, said walls and roof enclosing a long tunnel-like combustion chamber C. The furnace walls are carried by longitudinally extending angle bars 3, 3 structurally secured to the vertical angle bars 4, 4 equally spaced along the sides of the furnace wall and also serving as buck-stays for the furnace. Bracket members 5, 5 are secured to the bottom flanges of angle bars 3, 3 and help to carry said walls. Opposite buck-stays 4,

4 are connected at the top by angle bars 6, and the buck-stays on each side of the furnace are maintained in spaced relation by channels 7. Thus, the walls 1, 1 and furnace roof 2 which together constitute the upper section of the furnace are carried by the angle bars 4, 4 through the brackets 5, 5 beneath which the traveling section A of the furnace operates.

The traveling section A of the furnace operates immediately below brackets 5, 5. Said section A 10 operates in intimate relation with longitudinally extending channels 9, 9 below the brackets 5, 5 and spaced therefrom, said channels being carried by a series of angle bars 10 extending between opposite buck-stays 4, 4 and secured thereto.

The combustion chamber C is divided into two zones by disposing the part of the roof 2' at the feed end of the furnace considerably lower than the main roof 2 and dropping down from the inner end of the roof section 2' a baffle b. The zone z below the roof section 2', while a part of the combustion chamber C, acts primarily for preheating the charge prior to combustion, while the zone z' serves as the combustion chamber proper wherein the combustion of the material proceeds for the purpose of completely incinerating the same. At the forward end of the zone z is a feed hopper H for receiving the more finely divided material of graded size, and above the rearward end of the zone z, and utilizing a platform portion 8 of the roof 2' as a support for the material, is a second hopper H' wherein the coarser, ungraded material is charged. Below the hopper H' there is constructed a suitable throat 11 through which the material feeds from the hopper, said throat having a discharge opening 12 leading into the combustion chamber zone z', and an opening 13 opposite thereto through which operates a hollow rectangular plunger 14 secured to the end of a piston 15 operable in cylinder 16 of a hydraulic ram. The construction of the ram forms no part of the present invention and, therefore, will not be described in detail, but let it be understood that it follows the conventional arrangement of devices of this kind in that it may be operated either by water or oil under the control of properly located and actuated valve mechanism. The function of the ram is to carry the plunger 14 through the throat 11 of the hopper and thereby eject material therefrom and feed the same into the combustion chamber C. In its operation the top plate of the plunger 14 serves to support the material m' as it moves through the hopper on its forward stroke, the bottom plate riding on the platform 8 and the end wall, obviously, ejecting the material from the hopper throat. The hopper H is of conventional form and has its outlet 17 at the bottom so as to discharge the material onto

the moving support (about to be described) whereby it is carried into the zone z . The moving support for the material comprises a series of pallets 19, the side walls 20, 20 of which are connected by cross bars 21, said pallets also being provided with suitable grates G, which form the air pervious supporting surface for the charge of material. The construction of the pallets and the construction of the grates is immaterial as far as the present invention is concerned and will, therefore, not be described in detail. However, adjacent pallets are interconnected through bars 22 at which points they have free hinge movement so that they may travel around the end sprocket wheels 23 and 24 as an endless conveyor. The chain of pallets are driven by a motor M directly connected with shaft 25 on which sprocket 24 is mounted. An air-box 26, supported by suitable structural members 27, is immediately beneath the pallets 19 and extends almost from one end to the other of the combustion chamber zone z , suitable dead plates 28, 28 being arranged at both ends of the air-box 26 to insure a practically air-tight joint around the upper margins of said air-box so that when suction is applied thereto the gases from the combustion chamber will be drawn downwardly through the charge on the pallets 19 into the air-box 26. This suction is induced by a blower 29 connected by a suitable conduit 30 to one side of the air-box 26, said blower also having a connection with the combustion chamber C adjacent to its discharge end through a conduit 31. Thus the products of combustion that pass into the air-box 26 are discharged into the zone z' of the combustion chamber C. A second air-box 32 is disposed beneath the chain of pallets 19 and extending substantially throughout the length of the zone z' of the combustion chamber. The purpose of the second air-box being to distribute a blast of air to the under side of the pallet grates causing said air blast to pass upwardly through the grates and the material thereon into the zone z' of the combustion chamber. A blower 33 connected to the air-box 32 by means of a conduit 34 supplies the blast to said air-box. Between the two air-boxes 26 and 32 I provide an igniting furnace 35 comprising essentially a closed chamber 36 open at the top in close proximity to the under side of the pallets 19, and slightly beyond the baffle b which separates the combustion chamber into the two zones z and z' . A suitable burner (which is not shown but may be similar to that described in my co-pending application, Serial No. 685,820, filed August 19, 1933) feeds a mixture of liquid fuel and air to the combustion chamber 36, and when the same is ignited said chamber is completely filled with flame and hot gases under pressure which forces the products of combustion upwardly through the pallet grates into intimate contact with the material thereon whereby said material become ignited.

In the operation of my invention, the hoppers H and H' are charged with material that is to be incinerated. The material m that is charged into the hopper H is more finely divided than that charged into the hopper H' and is graded so that the particles composing the material will be of substantially uniform size, such that will pass a 1½" screen. The material m' charged into the hopper H' is not graded and is not of uniform size but consists of a mixture of rubbish, garbage, broken boxes and paper. The bottom of the hopper H is open and the material continuously discharges from said hopper onto the grates of

the chain of pallets which comprise the support for the material as it travels through the furnace. As the pallets move under the hopper H the bottom edge e of the hopper cuts off the flow of material so that it arranges itself in the pallets in the form of a layer (as shown in Fig. 2). The layer of the material m is carried through the zone z of the combustion chamber and immediately after passing the baffle b the material m' from the hopper H' is charged on top of it. Obviously, the feeding plunger 14 is operated at the proper speed so that the correct amount of material discharged from the hopper H' will be ejected therefrom into the zone z' of the combustion chamber C. When the material comes over the igniting furnace 35 the flaming particles and hot gases therefrom will be forced into the bottom surface of the layer of material m , effecting ignition thereof from one side to the other. As the pallets travel through the zone z' the combustion of the material m will proceed upwardly through the layer and the heat and flaming particles produced by such combustion will of course ignite the material m' superincumbent thereon. The combustion of both components of the material m and m' will then continue as the material is carried through the zone z' of the combustion chamber C. Obviously, as the material is consumed the bulk thereof will decrease until finally as the top of the material reaches the discharge end of the pallets it will be in the condition of a compact, porous mass of cinder. I have found in practice that the effect of the draft through the combustion chamber C induced by the stack S thereof will draw the flaming particles and the heat of the burning mass rearwardly, as shown by the feathered arrows (Fig. 2), so that kindling of the mass of material m' in the zone z' will be retarded unless some means is provided for counteracting the effect of the draft in zone z' . I, therefore, have dropped the roof 2' near the feed end of the combustion chamber C closer to the charge of material and have provided the baffle b to create a separate zone z through which only the layer of the material m passes. A suction is maintained downwardly through the layer of material m by means of the air-box 26 and blower 29, under the influence of which the flame and hot gases from the igniter 35 and the combustion of the material immediately thereabove are drawn into the zone z , and to a certain extent opposing and counteracting the effect of the draft through the zone z' . The plain arrows indicate the flow of the gases through the zone z , thus, the flame and heat incident to the ignition of the material is held close to the baffle b so that by the time the material moves any considerable distance into the zone z' it will be undergoing rapid combustion. Thus, practically from the very beginning of the zone z' the material will be burning, and by the time it reaches the end of said zone will have been entirely consumed except for the cinder residue. The gases that are drawn through the zone z and into the air-box 26 are discharged into the zone z' so that these gases will be subjected to the intense heat therein and will be completely oxidized. Therefore, any gases that reach the stack S will already have passed through the purifying heat of the zone z' and will be free of any odor.

Another advantage of the flow of hot gases from the zone z' to the zone z and through the layer of material m is the partial drying and heating of said layer to facilitate the ignition thereof, and at the same time furnishing a quick exit from the mass of material at the feed end of the

zone z' for the large volume of gases given off from this material immediately after it is kindled. The function of the baffle b is to deflect the hot gases and flaming particles forced into the material by the ignition furnace 35 downwardly into close contact with the surface of the layer of material m , thus making a more thorough job of the ignition of the material comprising said layer. In other words, the suction induced by the box 26 10 cooperates with the baffle b to concentrate the flame from the ignition furnace in the region of said baffle so that the material will be thoroughly kindled as it starts on its travel through the zone z' .

15 After the material has been completely burned the residue is dumped from the pallets into a hopper H'' , from which point it may be transported or handled as desired.

Having described my invention, I claim:

20 1. An incinerating furnace having a combustion chamber and a preheating chamber in alignment and in communication, a traveling grate forming the bottom of said chambers and movable from the preheating chamber through the combustion chamber, means for charging material on the grate at the entrance to the preheating chamber, means for charging additional material thereon at the entrance to the combustion chamber, means in the region of the junction of 25 the chambers for applying flaming particles to the material on the grate, means for causing air and hot gases to travel from the preheating chamber downwardly through the charge, and means for causing air to move upwardly through 30 the charge to the combustion chamber.

35 2. An incinerating furnace having a combustion chamber and a preheating chamber in alignment and in communication, a traveling grate forming the bottom of said chambers and movable from the preheating chamber through the combustion chamber, means for charging material on the grate at the entrance to the preheating chamber, a baffle between the preheating chamber and the combustion chamber for deflecting the hot gases downwardly as they enter 40 the preheating chamber, means for charging additional material thereon at the entrance to the combustion chamber, means in the region of the junction of the chambers for applying flaming particles to the material on the grate, means for causing air and hot gases to travel from the preheating chamber downwardly through the charge, and means for causing air to move upwardly 45 through the charge to the combustion chamber.

50 55 3. An incinerating furnace having an elongated combustion chamber, a traveling grate forming the bottom of said combustion chamber, means for feeding material onto said grates, means for discharging material from the grates, a baffle within said combustion chamber, means for applying flaming particles to the material in the region of the baffle, means for drawing hot gases downwardly through the material between the feeding means and the baffle, and means for 60 passing air upwardly through the material between the baffle and the discharge means.

65 70 4. An incinerating furnace having an elongated combustion chamber, a traveling grate forming the bottom of said combustion chamber, means for feeding material onto said grate,

means for discharging material from the grate, a baffle within said combustion chamber, means for forcing hot gases and flaming particles upwardly into the material in the region of the baffle, means for drawing hot gases downwardly 5 through the material between the feeding means and the baffle, and means for passing air upwardly through the material between the baffle and the discharge means.

5. A furnace comprising a combustion chamber 10 and a pervious support forming the bottom of said chamber, means for charging material onto said support, means for discharging material therefrom, means for moving said support through the combustion chamber, a baffle in the 15 combustion chamber forming a narrow passage between its lower edge and the material support, an igniter disposed below the pervious support and arranged to project flaming particles against the charge in the region of the baffle, means for 20 causing a supporter of combustion to traverse the support, and means for causing gases to move from the part of the combustion chamber between the baffle and discharge end of the chamber to the part of the combustion chamber between 25 the baffle and charge end of the chamber.

6. A furnace comprising a combustion chamber and a pervious support forming the bottom of said chamber, a baffle in said chamber and spaced from the pervious support, means at one end of 30 the combustion chamber for charging material as a layer on said support, means for causing said support to travel beneath said baffle, means for charging additional material on said layer beyond the baffle, means for igniting the bottom 35 surface of the bottom layer in the region of the baffle, means for causing hot gases to pass downwardly through said layer between the charging end of the chamber and the baffle, and means for causing a supporter of combustion to traverse 40 the material beyond the baffle.

7. An incinerating furnace having a combustion chamber and a preheating chamber in alignment and in communication, a traveling grate forming the bottom of said chambers and movable from the preheating chamber through the combustion chamber, means for charging material on the grate at the entrance to the preheating chamber, means for charging additional material thereon at the entrance to the combustion 45 chamber, means in the region of the junction of the chambers for applying flaming particles to the material on the grate, means for exhausting the hot gases from the preheating chamber, and means for causing air to move upwardly through 50 the charge to the combustion chamber.

8. An incinerating furnace having an elongated combustion chamber, a traveling grate forming the bottom of said combustion chamber, means for feeding material onto said grate, 60 means for discharging material from the grate, means for forming an auxiliary chamber within the combustion chamber near the feed end thereof, means for applying flaming particles to the material as it leaves the auxiliary chamber, 65 means for passing air upwardly through the material in the combustion chamber, and means for maintaining an independent draft through the auxiliary chamber.
